UNITED STATES PATENT OFFICE.

ROBERT FARIES, OF DECATUR, ILLINOIS.

MACHINE FOR FORMING INTERLOCKING-EYES.

SPECIFICATION forming part of Letters Patent No. 321,013, dated June 30, 1885.

Application filed September 10, 1884. (No model.)

To all whom it may concern:

Be it known that I, ROBERT FARIES, a resident of the city of Decatur, county of Macon, and State of Illinois, have invented certain new and useful Improvements in Machines for Forming Interlocking-Eyes, of which the following is a specification.

My invention relates to the construction and arrangement of mechanisms by means of which interlocking-connections are formed between sections of wire; and it consists in the various parts and combinations set forth in the appended claims.

In the drawings accompanying and forming a part of this specification, Figure 1 is a front elevation of my machine. Fig. 2 is a plan of the platform formed on the upper end of the upper portion of my interlocking device. Fig. 3 is a longitudinal diametrical section of a shaft and pulley used to secure the interlock by coiling the free ends of the wire around the body of the same. Fig. 4 is a longitudinal diametrical section of the upper portion of my interlocking device. Fig. 5 is a perspective view of the principal parts of the mechanism employed. Figs. 6, 7, and 8 serve to illustrate various steps in the operation of the interlocking device. Fig. 9 shows the connection of the wire half formed, and Fig. 10 represents the same completed.

As indicated in Fig. 1, my invention may be classed in three divisions: First, the upper portion of the interlocking device; second, the lower portion of the same; and third, the mechanism employed to coil the free ends of the wire around the body of the same after the interlock has been effected.

The reference-letters refer to various parts, as follows:

- 40 *a* is a platform rigid on vertical shaft *r*.
- b* (see Fig. 2) is a segmental guide-ridge elevated from the upper surface of platform *a*.
- c* is a spur projecting upward and outward from the circumference of the platform.
- 45 *d* is an elevation lying in an approximately radial position on the platform, and *e* is a vertical inclination on the same.
- f* *f'* is a bent lever, provided with a fulcrum in frame *g*.

g' is a rod that extends from lever *f* through 50 shaft *r*. (See Fig. 4.)

h h are friction-pulleys rigidly attached to cylindrical shaft *h*'. (See Fig. 3.)

i is a vertical tubular standard rigidly attached to the frame of the machine. 55

k k, in Fig. 1, are braces that operate in a manner to be hereinafter set forth.

l l are rotating arms rigidly attached to shafts *h*' of wheels *h*.

m m, as indicated by dotted lines in Fig. 1, 60 are bent levers, connected with an operating-bar by means of rods *m' m'*. A spring, *m''*, also connects with the operating-bar above mentioned, holding said bar and levers in the position indicated. 65

n is a beveled friction pulley, supported in upright *r'* and operated by belt-pulley *o*. (See Fig. 1.)

p, in Fig. 3, is a tubular shaft having a limited amount of free motion longitudinally in 70 shaft *h*'.

p' is a longitudinal groove in shaft *p*, and *p''* is a short groove lengthwise of the same.

q represents a frictional spring in groove *p'*.

r is the shaft to which platform *a* is rigidly 75 attached, and *r'* is a support for said shaft.

s is a shaft to which frame *g* is rigidly attached.

t is a shaft having a limited amount of rotary motion in standard *i*. 80

u is a lever used to partially rotate shaft *t*.

v v are sliding plates on which pulleys *h h* have their bearings, and *w w* are guides for the same.

x represents upward projections on shaft *t*. 85

y shows downward projections from shaft *s*.

z indicates the wire. The spring 4 in Fig. 4 tends to hold the wire firmly between the ends of shafts *s* and *t* while the eyes are being formed. 90

In operation the wire is passed through tubular shaft *p* and the ends placed in the position indicated in Fig. 5. The lever *f* is then lowered into the vertical bifurcated guide-piece of frame *g* and lever *u* turned to the 95 right, as shown in Fig. 6. The result of this operation is to bring shaft *s* in contact with the wire, to cause the lower end of rod *g'* to

penetrate the opening in shaft t and to slightly deflect the wire. A further step in the operation consists in rotating lever f to the left until its bent end f' comes in contact with spur 5 c , as shown in Fig. 8. Fig. 7 shows the above-mentioned result one-half effected, and the result is as follows: As the rotation proceeds the projections on shaft s engage the ends of the wire and bend 10 the same around the lower end of rod g' , while the block e' on frame g ascends incline e and raises the said ends clear of the body of the wire, thus overcoming all impediments to the operation. When the lever f' comes in contact with spur c , as shown in Fig. 8, the interlock will be formed, as indicated in Fig. 9. To complete the operation, shaft s is adjusted 15 as shown in Fig. 6, and shaft t as shown in Fig. 5, after which the ends of coiling-shafts 20 p are made to engage the free ends of the wire and motion is imparted to pulleys h h in opposite direction by contact with rotating bevel-pulley n , thereby effecting the coils, as indicated in Fig. 10. It is evident that the coiling-shafts must recede from each other while 25 forming the coils, and this is provided for in recess p'' , which permits said shafts to move longitudinally to a limited extent in cylinder h' . Friction-springs q are relied on to offer a 30 sufficient resistance to the receding motion of the coiling-shafts, and the disadjustment following the said receding motion is corrected after each operation by braces k k offering resistance to the ends of the shafts p and returning the same to their places. To enable the 35 wire to pass out of the machine after the interlock has been completed, a lateral opening is formed longitudinally in one of the coiling-shafts, and a cavity of sufficient size to permit 40 tie joint to pass, formed through cylinder h' . (See Fig. 5, where such an arrangement is indicated.) To cause the coiling-shafts to stop always in the same position, levers m m are made to engage arms l l after each operation. (See 45 Fig. 5.) When the lever f is in the position indicated in Fig. 5, its bent extremity rests between elevations b and d , supporting frame g and rod g' , and a downward motion of said lever on a vertical line will produce the position 50 shown in Fig. 6. The spring m'' , by operating through rods m' m' and bent levers m m , causes friction-pulleys h h to recede from each other after the completion of each coiling operation.

When the arms l move horizontally toward each other they become detached from the 55 slotted ends of the bent levers m m and permit friction-pulleys h h to rotate freely when they come in contact with pulley n , and when the said pulleys h h recede from each other their momentum is arrested by the ends of 60 arms l again coming in contact with the ends of the bent levers.

Having thus described my invention, I claim as new and desire to secure by Letters Patent—

1. A vertical tubular limitedly-rotating 65 shaft, t , provided with upward projections x , a vertical tubular rotating shaft, s , provided with downward projections y , a rod, g' , adapted to operate vertically in shaft s and reciprocatingly penetrate shaft t , and suitable means for 70 operating rod g' and rotating shaft s , all adapted to operate in combination for the purpose of effecting an interlock between two ends of wire, substantially as set forth.

2. The combination, in a machine for forming 75 interlocking-connections between two ends of wire, of a vertical tubular limitedly-rotating shaft, t , vertical tubular rotating shaft s , rod g' , frame g , block e' , lever f f' , and platform a , provided with spur c and incline e , as and 80 for the purpose set forth.

3. The combination of shafts t s , rod g' , frame g , levers f f' , and platform a , provided 85 with spur c , incline e , segmental elevation b , and radial elevation d , as and for the purpose set forth.

4. The combination of tubular rotating shaft 90 s , tubular shaft t , having a limited amount of rotary motion, standard i , and lever u , as and for the purpose set forth.

5. The combination of cylindrical shafts h' , provided with rotating pulleys, tubular shaft p , provided with slots p' p'' , and friction-spring q , located in slot p' , all constructed and arranged to co-operate for the purpose of coiling 95 an end of wire around the body of the same, as set forth.

6. The combination, with cylindrical shaft h' , provided with friction-pulley h , slotted shaft p , and spring q , of brace or bumper k , 100 constructed and arranged to operate as and for the purpose set forth.

ROBT. FARIES.
